UNITED STATES PATENT OFFICE.

ELI STRONG, OF KALAMAZOO, MICHIGAN.

ROLLER-MILL.

SPECIFICATION forming part of Letters Patent No. 288,886, dated November 20, 1883.

Application filed August 17, 1883. (No model.)

To all whom it may concern:

Be it known that I, ELI STRONG, a citizen of the United States, residing at Kalamazoo, county of Kalamazoo, State of Michigan, 5 have invented a new and useful Roller-Mill, of which the following is a specification.

The object of my invention consists in certain improved features of construction, to facilitate the operation and increase the utility 10 of roller-mills.

In the drawings forming a part of this specification, Figure 1 is an elevation of a portion of a roller-mill, looking against the ends of the rollers, certain parts being broken away; 15 Fig. 2, a top broken view of the device, showing about one-fourth of the whole; and Figs. 3, 4, and 5 are enlarged details, hereinafter explained.

B represents a supporting-frame, upon which 20 the boxes which form bearings for the rollers R R' are located. Two of the rollers, R', termed "stationary" rollers, have bearings at each end in the double stationary box D. The other adjustable rollers, R, have bearings at 25 each end in the adjustable or sliding boxes E. A divided rod, t a, adjustably coupled together by thimbles C C, is extended through the boxes D E, beneath the bearings of the rollers R R', and terminates at each end in a 30 hand-wheel, F. The thimbles are located in recesses in boxes E, Fig. 1. Said thimbles have threaded perforations, in which threaded portions of the rods are located. By turning the hand-wheel F, the adjustable roller R is 35 moved toward or from the stationary roller R'.

The construction shown in the drawings illustrates one side of the device, the opposite side being the same.

When the hand-wheel F is turned, the 40 thimble C runs off or on the threaded end of rod a. Boxes E are movably located on the frame B. S is a stud connected with box E, and extending through the frame in an elongated slot, to prevent lateral displacement 45 of the sliding box E. Bolts i i prevent the stationary double box D from rising up during the action of grinding. Bolts x x are used to vertically adjust the double box D to the desired height in relation to the movable rollers R. By loosening bolt i and turning up bolt x, the box D is raised, and the reverse

operation lowers said box. Tension-springs r r are located on the adjusting-rod t, and in a recess in box E. (See left of Fig. 1.) Jam-nuts v are located on this rod, to adjust the tension 55 of spring r. By this combination of parts, the adjusting-rods and tension-springs are in immediate relation with each other; yet the operation of one does not interfere with the action of the other. The sliding box E has a 60 rear extension, S', extending from the box bearing to the hand-wheel F. The office of this extension, aside from supporting the end of the adjusting-rod t a, is to act as a brace, preventing the end of the box E, which supports the roller R, from tilting up during 65 the operation of grinding.

In the construction of the mill, the rollers R R' are to be serrated around their peripheries, according to the construction of such rollers 70 for grinding grain.

The adjustment of the rollers thus far described relates to the degree of fineness which they grind the grain. When the mill is at rest, it is desirable that the rollers R should 75 be moved away from the rollers R' without interfering with their adjustment in regard to fineness of grinding the grain. Effect this by locating a shaft, e, across the frame between the stationary rollers R', said shaft e 80 having bearings at each end in the stationary boxes D, Figs. 1 and 2. This shaft is provided with two eccentrics, c c', with which the eyes b of the rods a are coupled, as in Fig. 2. The shaft e is revolved by means of a 85 lever, l. The construction of the eyes b and the double eccentric c c' is shown in Figs. 3, 4, and 5. Throwing the lever l from its position in Fig. 1 toward the right hand would move both rollers R, with their boxes E E, away 90 from the stationary rollers R'. When the lever was thrown back preparatory to starting the mill, the prior adjustment of the rolls would remain the same.

Having thus described my invention, what 95 I claim as new is—

1. The combination, with the double stationary boxes, stationary rollers, and the rotating shaft, having double eccentrics and operating-levers, of the sliding boxes, adjustable rollers, the divided adjusting-rods extending through the boxes, the threaded coup-

ling-thimbles, and hand-wheels, all substantially as set forth.

2. The combination, with the double stationary boxes and sliding boxes, of the divided 5 adjusting-rods, coupling-thimbles, tension-springs, and jam-nuts, substantially as described.

3. The combination, with the stationary and movable boxes, the latter having the rear ext-10 tensions serving the double purpose set forth,

of the adjusting-rods, substantially as de-scribed and shown.

In testimony of the foregoing I have here-unto subscribed my name in the presence of two witnesses.

ELI STRONG.
